The ornamental design for a liquid spray nozzle air directing cap, as shown and described.

DESCRIPTION

FIG. 1 is a perspective of a liquid spray nozzle air directing cap embodying the design of the present invention;

FIG. 2 is a top plan view of the air cap;

FIG. 3 is a front elevational view of the air cap, the rear elevational view being a mirror image thereof;

FIG. 4 is a right side elevational view of the air cap, the left side elevational view being a mirror image;

FIG. 5 is a bottom plan view of the air cap;

FIG. 6 is a longitudinal section of the air cap taken in the plane of line 6—6 in FIG. 2 for the purpose of facilitating better understanding of the top and bottom plan views;
